HOBBYHORSE HEAD

Judith C. Loven, 18 Concord St.,
Glastonbury, Conn. 06033

Filed July 24, 1974, Ser. No. 491,324

Term of patent 14 years

Int. Cl. D21—01

U.S. Cl. D34—15 AE

FIG. 1

FIG. 3

FIG. 1 is a side elevational view of a hobbyhorse head showing my new design, the opposite side being a mirror image thereof;

FIG. 2 is a front elevational view thereof; and

FIG. 3 is a top plan view thereof also showing the rear thereof in perspective.

I claim:

The ornamental design for a hobbyhorse head, substantially as shown and described.
